BOX FOR CRAYONS OR SIMILAR ARTICLE

Walter R. Huston, Napoleon, Ohio

Application October 27, 1952, Serial No. 21,997

Term of patent 7 years

(Cl. D58—11)

To all whom it may concern:

Be it known that I, Walter R. Huston, a citizen of the United States of America, residing at Napoleon, Henry County, Ohio, have invented a new, original, and ornamental Design for a Box for Crayons or Similar Article, of which the following is a specification, reference being had to the accompanying drawing, forming a part thereof.

Fig. 1 is a perspective view of a box for crayons or similar article, showing my new design; and

Fig. 2 is a horizontal medial section of the box, shown in Fig. 1.

I claim:

The ornamental design for a box for crayons or similar article, as shown.

WALTER R. HUSTON.
